[57] CLAIM

The ornamental design for a combined vehicle floor pan
and integral side running boards and fenders, as shown.

DESCRIPTION

FIG. 1 is a front elevational view of a combined vehicle
floor pan and integral side running boards and fenders
showing my new design;

FIG. 2 is a rear elevational view thereof;

FIG. 3 is a left-end elevational view thereof;

FIG. 4 is a right-end elevational view thereof;

FIG. 5 is a top plan view thereof; and

FIG. 6 is a bottom plan view thereof.
